CHARGER-READER

Ole G. Landsverk, Mount Healthy, Ohio

Application June 1, 1950, Serial No. 165,481

2 Claims. (Cl. 250—83.6)

1

This invention relates to improved apparatus for reading and charging ionization chambers of the condenser type used for gamma and X-radiation dosimetry. Such ionization chambers consist of a cylindrical conducting shell with an insulated central electrode and a gas, usually air, surrounding the central electrode within the cylinder. They constitute a tubular capacitor in which the air is the dielectric. When such chambers are provided with means for fastening to the clothing or wearing on the person, they are usually referred to as pocket chambers. Without such provision, they are usually called thimble chambers.

A known potential difference is established between the central electrode and the cylinder by means of a charging apparatus. When ionizing radiation penetrates the chamber, ions are formed in the gas, and a current flows resulting in a loss of charge on the central electrode. The amount of discharge can be measured using a reading apparatus and is a measure of the amount of radiation which has impinged on the chamber. The chambers must then be recharged before further use. The charging and reading is done by the same apparatus. Such an apparatus is here referred to as a charger-reader, and is the subject of this invention.

It is an object of this improvement to provide a convenient to use, pocket sized, portable, light weight, shock resistant charger-reader which requires no batteries for its operation, and is sealed against dirt and moisture for use with thimble and pocket chambers of a specific type in gamma and X-radiation dosimetry.

Other objects and advantages of the invention will become evident from the following description when read in connection with the accompanying drawing in which:

Figure 1 is an enlarged cross-sectional view of the charger-reader unit.

Figure 2 is an enlarged longitudinal cross-sectional view of the microscope and electrometer assembly.

Figure 3 is an enlarged longitudinal cross-sectional view of the electrostatic charger and switch mechanism.

Figure 4 is a section of the view of Figure 3 along line 4—4.

Figure 5 is an enlarged longitudinal cross-sectional view of the thimble or pocket chamber socket assembly. A typical ionization chamber of the condenser type is shown inserted in the socket for charging and reading.

Throughout the drawing and the specification, like reference characters indicate like parts.

2

Referring more particularly to Figure 1, the charger-reader consists of a chassis 1 a portion 2 of which is shaped to form a fingerhold, a quartz fibre electrometer and microscope assembly 3, an electrostatic charger assembly 4, an ionization chamber socket assembly 5 and a window to admit light to the microscope 6. A pocket chamber 7 is shown in the socket of the charger-reader ready to be charged or read.

10 The ionization chambers that are used with this charger-reader are the subject of application for Letters Patent Serial No. 134,385 filed December 22, 1949 by the undersigned inventor and are referred to therein as pocket chambers.

15 Such chambers are approximately $1\frac{7}{16}$ " long by $\frac{1}{2}$ " in diameter. If they are of such construction as to give a full scale reading after exposure to 0.2 to 2 roentgens, they are referred to as low range pocket chambers or low range thimble chambers. When they give a full scale reading after exposure to radiation amounts in the range from 10 to 200 roentgens or more, they are referred to as high range pocket chambers or high range thimble chambers.

20 In Figure 2 is shown a section of the quartz fibre electrometer and microscope assembly. This consists of an elongated hollow cylinder of conductive material 8, having within it at one end a charge responsive unit consisting of a very fine charge sensitive platinum coated quartz fibre 9 mounted on support wire 10. This system is supported by polystyrene insulator 11. A microscope is located within the cylinder at the opposite end. This consists of chassis 12 with objective lens aperture 13 as an integral portion of it and O-ring 14 for holding objective lens 15 in place. O-ring 14 is pressed against objective lens 15 by conducting sleeve 16 which is shaped to form objective lens aperture 17 and is itself cemented into the end of chassis 12.

25 Chassis 12 is molded of black polystyrene. It has a sleeve at its upper end which is solvent welded into a socket of eyepiece shell 18 so as to press against the edges of and hold securely eyepiece scale 19. Eyepiece shell 18 is also molded of black polystyrene. Shell 18 has eyepiece lens 20 molded into it near its upper end so lens 20 is in focused relation with scale 19.

30 It is seen that the microscope comprises an integral unit which slides into cylinder 8 and is centered and cushioned against shock therein by O-ring 50 and which can be adjusted so as to focus the image of fibre 9 on scale 19. Shell 18 is provided with a flange 21 for convenience in manipulating the microscope in obtaining an exact focus.

The entire microscope and electrometer assembly which is shown in Figure 2 is the same general construction as is fully described in an application for Letters Patent by the undersigned dated January 10, 1950, Serial No. 137,783. Fully described there are the structure, function and techniques of constructing and adjusting the voltmeter assembly consisting of quartz fibre 9, support wire 10 and insulator 11. Similarly described are the relative positions and functions of objective lens 15, eyepiece chassis 18, eyepiece reticle 19, eyepiece lens 20, microscope chassis 12, conducting sleeve 16 and aperture 17, O-ring 50 for centering and shock-proofing the microscope and sealing it from dirt and moisture and O-ring 14 for applying continuous pressure to the objective lens. Described also are the various suitable mixtures and modes of fabricating conducting tube 8.

The microscope which is shown in Figure 2 differs from those in application No. 137,783 in the fact that both the eyepiece 18 and the chassis 12 are hollow shells instead of solid transparent cylinders. They are, therefore, preferably molded of opaque plastic materials such as black polystyrene.

The novel features of this microscope are as follows:

1. The microscope is all plastic.
2. An integral microscope is slipped into the hollow cylinder 8 to focus on an object which is mounted at the other end of the cylinder said object being the quartz fibre 9 of an electrometer. The microscope is then cemented in place. The flange by which the microscope unit was controlled during these manipulations is trimmed off at plane AA' after the cement is dried. This method of focusing is much simpler than methods now being used.
3. If the fibre action is not satisfactory as viewed by the microscope or the voltage range is not correct, tools may be inserted through a window 22 in the cylinder. Support wire 10 may be bent until proper action is obtained. This operation must be performed before the microscope is cemented into place. This method of adjusting is considerably more simple than those that are now in use for this type of instrument. Fibre support wire 10 extends through the insulator 11. The portion above the insulator becomes the charge-sensitive element which in this instrument serves as a very sensitive voltmeter. The portion that is below the insulator extends about $\frac{1}{8}$ " below the insulator flange. From that point a $\frac{1}{8}$ " long section is bent so the two parts form an upright but tilted V or crotch 23, Figure 2. The end of the charging electrode 24 is sprung into this crotch so as to make a sliding contact with it, the apex of the crotch is somewhat off the line which is the normal position of electrode 24.

Referring to Figure 3, the charging unit consists of a mounting plate or disc 25, a rotator 26 with a knob 27, O-rings 28, insulating support tube 29, metallic support strips 30 and 31, charge pad 32 and charge 33, contact extension 34 to support strip 31, washer 35 whose shape constitutes a portion of a cylinder, contact arm 36, drive screw 37. Numeral 24 denotes the chamber socket electrode and 39 denotes the negative electrode which is a portion of the charger-reader chassis.

The charger consists of three dissimilar substances, felt charge pad 33, chamois charge pad 32, and polystyrene rotator 26 which is cylin-

drical and is positioned between the other two and is in intimate contact with them and which when rotated by the use of knob 27 generates an electrostatic charge. This is in conformity with the well known principle that if two dissimilar substances are rubbed together they become charged, one positively, the other negatively. In this case the polystyrene will remove electrons from the felt charger pad and supply electrons to the chamois thus giving the former a positive and the latter a negative charge.

Contact arm 36 is attached to the outer end of rotator 26 and rotates with it because a disc shaped part of it is squeezed between rotator 26 and cylindrical washer 35 by drive screw 37 thus forming a friction clutch. When the contact arm encounters electrode 24 or grounded member 39 the clutch slips thus maintaining contact as cylinder 26 rotates and charging continues in the first instance or the charger is grounded in the second instance.

Figure 4 shows a section along line 4-4 of Figure 3. Insulating tube 29 has two slots cut parallel to its axis in which support strips 30 and 31 are held. The slots are cut at such distance from the axis of rotator 26 that charge pads 32 and 33 maintain suitable frictional contact with it. An extension 40 of strip 30 is so placed as to be in sprung contact with the chassis 1 when the charger is mounted in its socket. O-ring 38 seals the charger into the chassis.

Figure 5 shows the position of a pocket chamber in the socket during the process of charging and reading. The socket consists of shell 41, charging electrode insulator 42 mounted in an aluminum sleeve and flange 52, contact pin 43, compression spring 44 and chamber socket electrode 24. At the opening to the socket are ball and spring 45 for preventing the chambers from falling out of the socket and to secure good contact between the socket shell and the chamber barrel. O-ring 46 seals the socket shell from dirt and moisture. The chamber barrel is numbered 51.

Chamber 7 is shown with its cylindrical, charged electrode 47, insulator 53, flexible diaphragm 48 and diaphragm pin 49. When chamber 7 is pushed with a force of 4 to 6 pounds, contact pin 43 presses against pin 49 thus flexing diaphragm 48 and causing pin 49 to contact electrode 47.

Diaphragm 48 cannot be damaged by excess use of force because spring 44 will compress when a force of 10 pounds is applied to it until the chamber barrel stops against the bottom flange of shell 41.

The charger is novel in several respects, particularly in the way the charge pads are supported, in the general design which permits easy mounting in a hole of suitable diameter with automatic grounding of the negative charge pad and also in the automatic switching arrangement. This maintains electrical connection between the contact arm and the positive charge pad while the contact arm operates as a switch which by clockwise turning of rotator 26 charges the electrode, then sets it exactly to zero with a vernier like smoothness by a counterclockwise motion of the rotator and finally after counterclockwise rotation of about $\frac{1}{8}$ turn, discharges the charger so as to bring the fibre back to the scale if it is accidentally overcharged.

When a chamber and the electrometer is given a full charge the quartz fibre will be repelled by its support wire so that its image assumes a posi-

tion on the scale indicated as zero. The zero point represents a charge of about 200 volts. After the chamber has been exposed to radiation, the charge on the chamber has been reduced and when this charge is shared with that of the fully charged electrometer the resultant equilibrium position of the fibre image indicates the drop of voltage of the charger-reader and the chamber as a unit. This in turn is directly proportional to the quantity of radiation in Roentgens that has penetrated the ionization chamber.

The volume, the electrostatic capacity and the material in the wall of the ionization chamber, the electrostatic capacity of the electrometer, the length and diameter of the quartz fibre and the magnification of the microscope are chosen to achieve the desired full scale dosage range. The chambers are initially calibrated by means of a known dosage. To take care of variations in the above mentioned factors a length of scale is then chosen for the microscope from a number of sizes that are available such that the full scale dosage reading is accurate within about two per cent. Scales are marked directly in Roentgen units or in milliroentgens depending on whether the chambers are the high or low range type.

In addition to the adjustments that are described above, the electrometer and microscope assembly must be adjusted so that it will fulfill the following conditions:

1. The arc made by the portion of the fibre that the microscope views as it crosses the axis of the microscope must lie as nearly as possible in a plane perpendicular to this axis.

2. The fibre image must be caused to reach the mid point of the scale at approximately some predetermined desirable voltage of, say 150 volts.

3. The image of the fibre must remain perpendicular to the longitudinal axis of the scale over the observed portion of its travel.

4. Equal voltage changes to within about 5% must be required to move the fibre over segments of equal length at various parts of the scale.

5. The fibre must remain sharply in focus over the entire length of scale.

These conditions are only independent in part, but those skilled in the art can so manipulate the portion of the fibre support wire which is between the insulator and the fibre so as to satisfy these conditions.

To operate the charger-reader, the index and two neighboring fingers of the left hand are inserted into the fingerhold. The instrument rests in the palm of the hand and the thumb is placed against the edge of the chassis above the socket opening. Insert a chamber in the charger-reader as far as it will go with the use of only a slight amount of force. Look into the microscope and point the microscope barrel at a source of light so the microscope scale is illuminated. Adjust the fibre position to zero on the scale by rotating the charger knob with the fingers of the right hand. Move the fibre slightly past zero and then back it down to zero. This disconnects the charger. Now press the chamber into the socket with the thumb until it stops against the flange in the shell of the socket. Contact is made with the chamber electrode by the diaphragm pin during this operation. The position that is now assumed by the fibre image on the scale is the reading of the chamber in roentgens or in milliroentgens as the case may be. Now operate the charger until the fibre is again at zero of the scale. When the pressure of the thumb against the chamber is removed, the diaphragm discon-

ncts the charging pin from the socket and the chamber is charged.

Aside from the novel features of individual parts of this charger-reader the entire assembly is novel in a number of respects.

1. It weighs only five ounces. All units now available weigh from 4 to 10 pounds.

2. It is truly portable and pocket sized. Its chassis measures only $3\frac{1}{4}'' \times 2\frac{3}{4}'' \times 1''$. By way of contrast the smallest unit of which we know is $1\frac{1}{8}'' \times 4\frac{3}{4}'' \times 6\frac{1}{8}''$ and weighs eight to ten times as much.

3. It requires no batteries nor external source of power.

4. Its design is so simple that it has not one single connecting wire nor a soldered joint. All other units of which we know have many of each.

5. It is hermetically sealed as are certain other units but in this unit there is no cover which is difficult to seal since the component parts are mounted in a solid chassis in sockets that are provided therein. The seals are simple reliable O-rings and these need never be opened for replacement of batteries.

6. The unit fits the hand and is under perfect control. All operations of charging and reading feel natural. There is no feeling of a need for a third hand or a table support as is true of all charge readers that have been available up to date.

7. In summary this is the only design up to this time which is truly pocket sized, completely independent and fully portable.

From the above description of my invention it is apparent that I have provided an improved charger-reader for use with condenser ionization chambers in determining gamma and X-ray dosage.

40. What is claimed is:

1. In apparatus for charging an ionization chamber of the condenser type and for measuring the charge of such condenser, the ionization chamber being provided with an electrical contact for charging purposes, the combination which comprises a chassis provided with a socket projecting into the chassis from the outside and into which a portion of the ionization chamber carrying the contact fits slidably and also provided with a cavity extending from the bottom of the socket in the same direction as the socket, an elongated first conductor disposed in the cavity and extending in the same direction as cavity and socket and insulated from the chassis, one end of this first conductor being adapted to contact the contact of the ionization chamber when it is disposed in the socket, a static charger mounted in the chassis with an end adjacent to the cavity and extending transverse thereto, an electrometer of the quartz fibre type mounted in the chassis with an end adjacent to the cavity and extending transverse thereto, to the outside, in the same direction as the charger, the electrometer being farther away from the socket than the charger, rotatable means for operating the charger projecting outside the chassis and carrying switching means for contacting the elongated conductor, and another conductor connecting the electrometer to the elongated conductor.

2. In apparatus for charging an ionization chamber of the condenser type and for measuring the charge of such condenser, the ionization chamber being provided with an electrical contact for charging purposes, the combination

which comprises a chassis provided with a socket projecting into the chassis from the outside and into which a portion of the ionization chamber carrying the contact fits slidably and also provided with a cavity extending from the bottom of the socket in the same direction as the socket, an elongated first conductor disposed in the cavity and extending in the same direction as cavity and socket and insulated from the chassis, one end of this first conductor being adapted to contact the contact of the ionization chamber when it is disposed in the socket, a static charger mounted in the chassis with an end adjacent to the cavity and extending transverse thereto, an electrometer of the quartz fibre type mounted in the chassis with an end adjacent to the cavity and extending transverse thereto to the outside and provided with viewing means on the outside, rotatable means for operating the charger projecting outside the chassis and carrying switching means for contacting the elongated conductor, and another conductor connecting the elec-

trometer to the elongated conductor, the chassis being provided with a finger aperture in the portion thereof opposite the socket.

OLE G. LANDSVERK.
